UNITED STATES PATENT OFFICE.

WILLIAM HENRY HERBERT, OF CHICAGO, ILLINOIS.

PORTABLE STOOL.

SPECIFICATION forming part of Letters Patent No. 713,639, dated November 18, 1902.

Application filed May 17, 1902. Serial No. 107,712. (No model.)

To all whom it may concern:

Be it known that I, WILLIAM HENRY HERBERT, a citizen of the United States, residing in Chicago, in the county of Cook and State 5 of Illinois, have invented a new and useful Improvement in Portable Stools, of which the following is a specification.

My invention relates to improvements in stools, and more particularly to portable 10 stools.

The object of my invention is to provide a portable stool of a simple, neat, light, strong, durable, and economical construction capable of being packed in compact shape and 15 readily carried, thus adapting the stool for camping or outing purposes as well as other or ordinary use.

My invention consists in the means I employ to accomplish this object or result—that 20 is to say, it consists in the novel construction of parts and devices and in the novel combinations of parts and devices herein shown and described.

In the accompanying drawings, forming a 25 part of this specification, Figure 1 is a side elevation of a portable stool embodying my invention. Fig. 2 is a similar view with the packing-bag removed. Fig. 3 is a bottom view of the seat. Fig. 4 is a plan view showing the seat and base nested, the carrying-bag being removed. Fig. 5 is a side elevation showing the stool in nested form in the 30 carrying-bag. Figs. 6 and 7 are detail views showing the sections of the standard. Fig. 35 8 is an enlarged central vertical section. Fig. 9 is an enlarged plan view of the base. Fig. 10 is a detail side elevation of one of the arms of the seat-frame. Fig. 11 is a detail view of the base-thimble.

40 In the drawings similar letters of reference indicate like parts throughout the figures.

In the drawings, A represents the central thimble of the base, the same consisting of a short section of steel tubing provided with 45 four vertical slots *a* near its lower end to receive the curved hook-shaped tongues *b* of the base-legs B. The base-legs B are stamped out of sheet-steel and provided with upright shoulders *b'*, which abut against the base-thimble A. Between the projecting lower end or rim *c'* of the thimble A and the shoulder *b''* of the tongues *b* a locking-thimble C,

consisting of a short section or ring of steel tubing, is inserted, and a steel locking-ring D, having a slightly tapering or wedging exterior, is forced inside the central thimble A down upon the curved tongues *b*, thus securely locking the sheet-steel legs B to the central thimble A. The legs B are braced and stiffened laterally or radially by sheet-steel braces E, having curved portions *e*, fitting the thimble A, and arms *e'*, which fit against the sides of the legs B and to which the same are secured by rivets *e''*. The legs B have at their outer ends tongues or projections *b''*, which are inserted through suitable openings in the circular sheet-steel feet or disks B' of the base and by which said feet or disks are secured to the legs, the tongues *b''* being upset or riveted. 70

F is the central thimble of the seat-frame, the same being identical in construction with the base-thimble A, excepting that the vertical slots *f* are at its upper instead of at its lower end. The arms G of the seat-frame are 75 of sheet-steel and of similar construction to the arms B of the base-frame and are provided with curved hook-tongues *g*, having shoulders *g'* to engage the locking-ring H, which is driven inside the central thimble F. At 80 the lower end of said thimble F a locking-ring H' bears against the tongues *g* on the opposite side, securely locking the arms G in position in the central thimble F. Sheet-steel braces K, having curved portions *k* to fit the 85 thimble F, and flat arms *k'*, fitting against the sides of the arms G and secured thereto by rivets *k''*, are provided for the seat-frame, similar to the sheet-steel braces E of the brace-frame. The locking-rings H' and D also 90 serve as stops, against which the ends of the sections M M' of the telescoping standard abut.

N is the seat, the same consisting, preferably, of a thin wood-veneer board furnished 95 with suitable perforations, as is customary in wood-veneer seats. The seat-frame arms G have straight upper edges *g''*, upon which the seat N rests and by which, in part, the same is supported. The sheet-steel seat-frame 100 arms G are also furnished with notches or recesses *g'''* to receive the sheet-steel seat-supporting disks G'. This causes said disks to be flush with the edges *g''* of the arms G. The

arms G also have tongues or projections g^4 , which are inserted through the disks G' and upset or riveted to secure the disks firmly to the arms G. The seat N is secured to the disks G' by rivets g^5 , which are inserted through the same and upset. The sections M M' of the standard are composed of light steel tubing, the section M' being furnished with a telescoped extension M² of less diameter, which fits within the section M.

P is the carrying-bag, the same being furnished with a gathering-cord p and a ring p', through which the looped end of the gathering-cord may be inserted. The carrying-bag 15 P is also furnished with a circular binding-cord P', slightly smaller in diameter than the thin veneer seat-board N, this cord being secured to the bag, so that when slipped or forced over the rim or the edge of the circular seat-board it will thus serve to keep the bag in position in relation to the seat. The locking-thimble C in exterior diameter corresponds to the tubular standard M M', so that when the telescoped standard is removed 20 from the thimbles A and F of the seat and base the locking-thimble C will fit within the thimble F, and thus secure the seat and base together, the latter in a reversed position. This will be readily understood from Fig. 8 25 of the drawings. A pair of flat steel springs R R' are preferably provided for holding the sections M M' of the standard when the stool is nested for carrying.

As in my invention the legs and arms of 30 the base and seat frames consist of sheet-steel pieces set edgewise and steel-tube thimbles firmly locked and braced together by the locking-rings and braces and as the sections of the steel-tube standard abut against the 35 locking-rings, the stool as a whole is exceedingly strong and durable and capable of supporting a great weight, while at the same time it is exceedingly light and may be manufactured very cheaply and economically.

40 When used as a portable stool for camping or outing purposes, the carrying-bag is a convenience and is preferably applied over the seat, as illustrated in the drawings. When my stool, however, is used as an ordinary 45 stool or for other than portable use, the carrying-bag may be omitted, and, if preferred, the steel-tube standard may be made in one piece.

I claim—

50 1. In a stool, the combination with a central steel thimble A having vertical slots a, sheet-metal legs B having hook-tongues b, locking-thimble C fitting in said thimble A and projecting beyond the lower end thereof, locking-ring D, sectional steel-tube standard M M', central seat-thimble F having vertical slots f, seat-supporting arms G having hook-tongues g, locking-rings H H', seat N, said locking-thimble C of the base fitting within 55 said central seat-thimble F when the standard is removed and the base reversed, substantially as specified.

2. In a stool, the combination with a central steel thimble A having vertical slots a, sheet-metal legs B having hook-tongues b, locking-thimble C fitting in said thimble A and projecting beyond the lower end thereof, locking-ring D, sectional steel-tube standard M M', central seat-thimble F having vertical slots f, seat-supporting arms G having hook-tongues g, locking-rings H H', seat N, said locking-thimble C of the base fitting within 60 said central seat-thimble F when the standard is removed and the base reversed, said base-legs B having integral tongues at their lower ends and metal feet-disks B', substantially as specified.

3. In a stool, the combination with a central steel thimble A having vertical slots a, sheet-metal legs B having hooked tongues b, locking-thimble C fitting in said thimble A and projecting beyond the lower end thereof, locking-ring D, sectional steel-tube standard M M', central seat-thimble F having vertical slots f, seat-supporting arms G having hook-tongues g, locking-rings H H', seat N, said locking-thimble C of the base fitting within 65 said central seat-thimble F when the standard is removed and the base reversed, said base-legs B having integral tongues at their lower ends and metal feet-disks B', substantially as specified.

4. In a stool, the combination with a central steel thimble A having vertical slots a, sheet-metal legs B having hook-tongues b, locking-thimble C fitting in said thimble A and projecting beyond the lower end thereof, locking-ring D, sectional steel-tube standard M M', central seat-thimble F having vertical slots f, seat-supporting arms G having hook-tongues g, locking-rings H H', seat N, said locking-thimble C of the base fitting within 70 said central seat-thimble F when the standard is removed and the base reversed, said base-legs B having integral tongues at their lower ends and metal feet-disks B', substantially as specified.

5. In a stool, the combination with a central thimble having vertical slots, of radial sheet-metal members having hook-tongues on their inner ends entering said slots and a locking-ring fitting within the central thimble and surrounding and embracing the shoulders of the hook-tongues of the radial sheet-metal members, said locking-ring fitting between 75 said central thimble and said shoulders of said hook-tongues, substantially as specified.

6. In a stool, the combination with a central thimble having vertical slots, of radial sheet-metal members having hook-tongues on their inner ends entering said slots, a locking-ring fitting within the central thimble and surrounding and embracing the shoulders of the hook-tongues of the radial sheet-metal members, and a further locking-ring fitting within 80 said thimble and bearing against said tongues on the radial members, said hook-tongues fitting between said locking-rings, substantially as specified.

7. In a stool, the combination with a central thimble having vertical slots, of radial sheet-metal members having hook-tongues on their inner ends entering said slots, a locking-ring fitting within the central thimble and surrounding and embracing the shoulders of the hook-tongues of the radial sheet-metal members, and a second locking-ring fitting within said thimble and bearing against said tongues on the radial members, said radial members having tongues on their outer ends and flat sheet-metal disks secured thereto and through which said tongues are inserted and riveted, said hook-tongues fitting between said locking-rings, substantially as specified.
8. In a stool, the combination with a central thimble A, furnished with slots *a*, of sheet-metal legs B having hooked tongues *b* furnished with shoulders *b*², of a locking-ring surrounding said shoulders and fitting within the thimble, substantially as specified.
9. In a stool, the combination with a central thimble A, furnished with slots *a*, of sheet-metal legs B having hook-tongues *b* furnished with shoulders *b*², of a locking-ring surrounding said shoulders and fitting within the thimble A and bearing against the tongues, substantially as specified.
10. In a stool, the combination with a cen-

tral thimble A, furnished with slots *a*, of sheet-metal legs B having hook-tongues *b* furnished with shoulders *b*², of a locking-ring surrounding said shoulders and fitting within the thimble, a locking-ring D fitting within the thimble A and bearing against the tongues, and braces E having curved portions *e* fitting the thimble and flat arms *e*² secured to and uniting the legs B, substantially as specified.

11. The combination with a slotted thimble of radial members having hook-tongues fitting in the slots of the thimble and provided with shoulders bearing against the exterior of the thimble and a locking-ring fitting within the thimble and embracing the hook-tongues, substantially as specified.

12. The combination with a slotted thimble of radial members having hook-tongues fitting in the slots of the thimble and provided with shoulders bearing against the exterior of the thimble, a locking-ring fitting within the thimble and embracing the hook-tongues and a second locking-ring engaging the opposite edges of the hook-tongues, substantially as specified.

WILLIAM HENRY HERBERT.
